UNITED STATES PATENT OFFICE

124,537

DESIGN FOR AN ELECTRIC ROASTER

Herbert J. Moon and Emmet G. Gardner, Milwaukee, Wis., assignors to National Enameling & Stamping Company, Milwaukee, Wis., a corporation of New Jersey

Application June 12, 1940, Serial No. 92,948

Term of patent 7 years

To all whom it may concern:

Be it known that we, Herbert J. Moon and Emmet G. Gardner, citizens of the United States, residing at Milwaukee, in the county of Milwaukee and State of Wisconsin, have invented a new, original, and ornamental Design for an Electric Roaster, of which the following is a specification, reference being had to the accompanying drawing, forming part thereof.

Figure 1 is a perspective view illustrating the front, top and one end of an electric roaster, showing our design;

Figure 2 is a diagrammatic view, taken along the sectional line 2—2 of Figure 1; and

Figure 3 is a diagrammatic view, taken along the sectional line 3—3 of Figure 1.

The dominant feature of our design resides in the front panel element of the electric roaster, shown in full lines.

We claim:

The ornamental design for an electric roaster, as shown and described.
